UNITED STATES PATENT OFFICE.

EDGAR R. HINMAN, OF ILION, NEW YORK.

TABLE.

SPECIFICATION forming part of Letters Patent No. 295,007, dated March 11, 1884.

Application filed July 12, 1883. (No model.)

To all whom it may concern:

Be it known that I, EDGAR R. HINMAN, of Ilion, State of New York, have invented a new and useful Improvement in Tables; and I do 5 hereby declare that the following is a full, clear, and exact description of the invention, which will enable others skilled in the art to which it appertains to make and use it, reference being had to the accompanying drawings, 10 forming a part thereof.

I am aware that folding tables have heretofore been made having jointed braces hinged to the cross-piece of the legs and directly to the under side of the table-top; but this construction is defective, because no means are provided to prevent the jointed braces from becoming shaky, and also fracture of the fastening to the table-top is liable and replacement uncertain.

20 To overcome these difficulties is the object of my invention, which consists in rigidly securing to the under side of the top of the table an oblong rectangular block, and on opposite sides thereof pivotally attached the 25 ends of the jointed braces; and my improvement also consists in means for retaining the table in a folded condition, to which end I fix on the sides of the rectangular block elastic plates, against the surfaces of which the 30 jointed braces press when the table is folded.

Figure 1 is a perspective view of my improved table, showing the same turned upside down and in a position for use; and Fig. 2 is a bottom view of the same, showing the 35 table closed.

Similar letters of reference refer to similar parts throughout the several views.

A represents the top of the table, to which are secured the legs B, which are connected 40 together by the cross-bar C, and which are secured to the table by the hinges D D.

To the cross-bar C is secured a brace or bar, I, to which the toggle-joint F is suitably pivoted, and the other end of said joint being piv-

oted to a block, G, secured in a longitudinal 45 position in the center of the table A.

On the side of the block G are placed rubber pieces H, for the purpose of holding the joint F when closed in a locked or rigid position.

50 To the table A are secured the brace-bars K K, which have the effect, when the table is in a position to be used, to hold the legs in a firm and strong position. (See Fig. 1.)

The operation is as follows: Supposing the 55 table to be in an open position, as shown in Fig. 1, all that it is necessary to do to close the same is to press up the toggle-joint F where it is pivoted together, thus bringing the two parts together, and at the same time drawing 60 the legs down so as to rest on the bottom of the table, and the toggle-joint, being pressed against the friction - pieces H, holds them in a secure and rigid position. (See Fig. 2.) To open the same, a reverse action is all that 65 is necessary to be done. When open, it will be seen that the legs B rest against the brace or bar K, and that the bar I rests upon the brace or bar K, thus firmly and securely preventing the legs B from being pushed out of 70 a vertical position.

Having thus described my invention, what I claim as new, and desire to secure by Letters Patent, is—

In combination with a table-top having 75 hinged legs and provided with jointed braces, the rectangular block G, provided with elastic plates and secured longitudinally to the under side of the table-top, and having pivotally attached on opposite sides thereof the jointed 80 braces, substantially as described, and for the purpose set forth.

In testimony that I claim the foregoing I append my signature.

EDGAR R. HINMAN.
